APPARATUS FOR RAILWAY TRAIN
SIGNALING SYSTEMS

Paul N. Bossart, Swissvale, Pa., assignor to The
Union Switch & Signal Company, Swissvale,
Pa., a corporation of Pennsylvania

Application August 22, 1934, Serial No. 740,929

11 Claims. (Cl. 246—8)

My invention relates to apparatus for railway train signaling systems, and particularly for railway train signaling systems which utilize the traffic rails as part of a communication circuit.

I will describe several forms of apparatus embodying my invention, and will then point out the novel features thereof in claims.

A feature of my invention is the provision in systems of the type here involved of more efficient and improved train-carried inductors. A further feature of my invention is the provision in such systems of receiving inductors immune to foreign space magnetic fields, together with inductors efficient for sending, the latter being connected with the receiving inductors and all of them used for sending. Another feature of my invention is the provision of apparatus wherein two or more inductors at points on the 20 equipped vehicle spaced apart are combined for sending and receiving and not only a large power transfer obtained but loss of signal at insulated rail joints is avoided.

For a better understanding of my invention reference may be had to the accompanying drawing in which Fig. 1 is a view partly diagrammatic and partly perspective of one form of multiple inductors embodying my invention. Fig. 2 is a diagrammatic view showing a modified arrangement for combining the multiple inductors of Fig. 1. Fig. 3 is a view partly diagrammatic and partly perspective, showing a second form of multiple inductors also embodying my invention. Figs. 4 and 5 are diagrammatic views showing a railway train equipped with apparatus embodying my invention, and wherewith loss of signal at insulated rail joints is avoided.

Similar reference characters refer to similar parts in each of the several views.

Referring first to Fig. 1, B1 and B2 are bars mounted on a vehicle of a railway train above and transverse to the traffic rails I and Ia. The method of securing the two bars B1 and B2 to the vehicle is not shown in order to simplify the drawing as much as possible, and it will be understood that the bars are held in place above the rails to clear all roadside equipment. These bars are preferably placed on the vehicle spaced apart along the trackway. For example, they may be mounted at the opposite ends of the vehicle. B1 and B2 each forms a structure on which inductor windings are wound and to this end the two bars may or may not be of magnetizable material. As will appear hereinafter, each of the bars B1 and B2 may be replaced by two independent bars,

one over each of said rails should it seem desirable to do so. As here shown, each bar, B1 and B2, is provided with four cores or legs, C1, C2, C3, and C4, each of which cores projects downward, the cores C1 and C2 being disposed on the opposite sides of the rail I, and the cores C3 and C4 being disposed on the opposite sides of the rail Ia. In the event the bars B1 and B2 are non-magnetic material, the several cores formed thereon may be located at the top of the bars and project upward if desired.

The cores, C1, C2, C3, and C4 of bar B1 carry coils, 10, 11, 12, and 13, respectively, and these coils are connected together in series to form an inductor winding which I shall refer to herein-after as inductor Ia. The coils 10, 11, 12, and 13 are preferably of substantially equal number of turns and resistances, and are so arranged that electromotive forces induced therein by magnetic flux created by an alternating current which flows in the two rails in multiple are additive. To visualize this arrangement the direction of current flowing in the traffic rails at a particular instance is indicated by double pointed arrows, and the direction of the flux about the rails at this particular instance as a result of such current, is indicated by dotted lines on which are placed single pointed arrows. It follows that the inductor winding Ia consists of four vertical coils or portions, two of which are disposed above and on the opposite sides of rail I, and the other two of which are disposed above and on the opposite sides of the rail Ia, and the separate coils are wound on the respective cores in a direction that when connected together in series, the electromotive forces induced in the different coils as a result of a current flowing in the rails in multiple add their effects. Furthermore, it is clear a foreign space magnetic field such as, for example, that produced by nearby power line and which field is illustrated in Fig. 1, by the arrows 14, will induce electromotive forces in the coils that cancel each other.

The cores C1, C2, C3, and C4 of the bar B2 carry coils, 15, 16, 17, and 18, respectively, and these coils are connected together in series to form a second inductor winding and which winding I shall refer to in the following description as inductor Ib. The coils 15, 16, 17, and 18 are not only preferably of equal turns and resistances with respect to one another but they are also preferably similar to the corresponding coils of inductor Ia. The coils 15, 16, 17, and 18 are wound on the respective cores in such manner that electromotive forces induced therein due to current

flowing in the traffic rails in multiple are additive. Consequently, the inductor winding I_b also consists of four vertical coils or portions, two of which are disposed on opposite sides of the rail 1 , and the other two of which are disposed on the opposite sides of the rail $1a$, the electromotive forces induced therein as a result of current flowing in the rails in multiple adding their effects, and the electromotive forces induced therein by a horizontal foreign space magnetic field cancelling each other.

The electromotive forces produced by the inductors I_a and I_b are added together and the total applied to the input of a receiving apparatus on the vehicles, a contact of a circuit controller being interposed in the connection. As here shown, the inductors I_a and I_b are serially connected with the receiving apparatus by a circuit which starts from the right-hand terminal of a filter F^1 and extends over back contact 19 of a directional relay DR , wire 20 , coils 18 , 17 , 16 and 15 of inductor I_b , wire 21 , coils 10 , 11 , 12 , and 13 of inductor I_a , wire 22 back contact 23 of the relay DR and to the opposite left-hand terminal of the filter F^1 the filter in turn being connected with the input of the receiving apparatus RA over wires 24 and 25 . The arrangement of the several coils of inductors I_a and I_b is such that not only the electromotive forces induced on the coils of each inductor are additive, but the electromotive forces of the two inductors combine and add their effects on the receiving apparatus RA . To illustrate this arrangement, arrows have been placed on the circuit elements to indicate the direction of the flow of current produced by the electromotive forces induced in the inductors I_a and I_b at the instant the rail current has the direction indicated by the double pointed arrows.

The receiving apparatus RA and the filter F^1 may take any one of several forms usually provided for railway train signaling systems of the type herein involved, and these devices are shown conventionally only for the sake of simplicity since the specific structure of such devices constitutes no part of my present invention. It is deemed sufficient for this application to point out that in railway train telephone systems, the receiving apparatus RA will ordinarily include a high gain amplifier and a demodulator effective to amplify and demodulate a carrier telephone current, and cause a current having the corresponding audio frequency to flow in the output to a telephone receiver such as a loud speaker LS . The filter F^1 will include a circuit network effective to suppress frequencies outside of the desired band and to pass the desired voice frequencies to the receiving apparatus.

It follows that the inductors I_a and I_b when taken together constitute a receiving inductor for transferring energy from the traffic rails to the receiving apparatus, and which inductor is balanced against the influences of a foreign space magnetic field transverse to the track, and which insures a relatively high sensitive pickup in response to a given current flowing in the traffic rails.

For sending, that is, inducing electromotive force in the rails, the balanced receiving inductor described above is not as efficient from the standpoint of its mutual inductance with the rails as an inductor mounted with its axis horizontal and directly above the rails as close as clearances permit. During the sending of current from the vehicle, the immune feature is of no advantage and hence inductors of relatively high mutual inductance to the rails are desired. The bar B^1 is provided with two coils 26 and 27 which are wound on the bar substantially above the rails 1 and $1a$, respectively. The coils 26 and 27 are preferably of equal turns and resistances and are connected in series to form a third inductor winding which I shall refer to as inductor I_c . Thus the inductor I_c consists of two horizontal coils one over each of said rails, the two coils being so connected and disposed that electromotive force induced in the two rails in response to current flowing in the coils are additive. In like manner, two coils 28 and 29 are wound on the bar B^2 , the coil 28 being substantially over the rail 1 and the coil 29 over the rail $1a$. These two coils 28 and 29 are connected together in series to form a fourth inductor winding which I shall refer to as inductor I_d . The coils 28 and 29 are preferably not only of equal turns and resistances with respect to each other, but are also similar to the corresponding coils of inductor I_c , and are so wound that electromotive forces induced in the rails as a result of current flowing in the coils are additive.

In Fig. 1, the four inductors I_a , I_b , I_c , and I_d are connected in series with the transmitting apparatus on the vehicle, and all of them are used for sending, a contact of the directional relay DR being interposed in the circuit. Starting from the lower terminal of the transmitting apparatus TA , a transmitting circuit can be traced over front contact 30 of relay DR , wire 31 , coils 28 and 29 of inductor I_d , wires 32 and 20 , coils 18 , 17 , 16 , and 15 of inductor I_b , wire 21 , coils 10 , 11 , 12 , and 13 of inductor I_a , wires 22 and 33 , coils 27 and 26 of inductor I_c , wire 34 , front contact 35 of relay DR and thence to the upper and opposite terminal of the transmitting apparatus TA .

The transmitting apparatus TA may take different forms and is shown conventionally only since its specific type constitutes no part of my invention. It is deemed sufficient to point out that for a railway train telephone system the apparatus TA will ordinarily include a generator of carrier frequency current, means for modulating the carrier with voice frequencies and an amplifier for amplifying the output to a relatively high energy level.

An analysis of the transmitting circuit traced above will disclose the fact that current supplied to the circuit from the apparatus TA , and which current at a given instance flows in the direction of the arrows placed on the circuit elements, will be effective to create fluxes about the rails as indicated by the dotted lines, the fluxes produced by the several coils adding in their effects. These several fluxes will induce electromotive forces in the rails that will cause a current to flow in the traffic rails in multiple in the direction indicated by the double pointed arrows, the return path for such current being through the ground in the manner described and claimed in the L. O. Grondahl application for Letters Patent, Serial No. 450,135, filed May 6, 1930, on Electric train signaling systems.

For a given energy output of the transmitting apparatus the power induced in the traffic rails is substantially doubled by the two similar structures B^1 and B^2 , when these two structures are far enough apart to be practically without mutual inductance to each other. In practicing my invention this condition will probably be realized by spacing the structures B^1 and B^2 on the vehicle along the track 4 or 5 feet apart with a clearance above the rails of from 5 to 6 inches. For a single inductor the magnetomotive force will be NI

where I is the current and N the number of turns. This magnetomotive force will produce a flux sufficient to induce an electromagnet force of say E_r in the rails and the power transferred to a rail circuit of the resistance of R_r will be $(E_r)^2/R_r$. For inductors of the same size, their resistance varies substantially as the square of the number of turns. Hence, when two inductors are used and the resistance of each is one-half the resistance of the one inductor of the former case so that the current output of the transmitting apparatus remains constant, the number of turns of each of the latter inductors will be

$$\sqrt{2}N = 2.$$

and the total turns of the two inductors will be

$$\sqrt{2}N$$

The flux produced by these two inductors will be correspondingly increased and the electromotive force induced in the rails will be

$$\sqrt{2}E_r.$$

Consequently, the power transferred to the rail circuit of the resistance R_r will be

$$\frac{(\sqrt{2}E_r)^2}{R_r}$$

or

$$2\frac{E_r^2}{R_r}$$

just double that obtained by the use of a single inductor. A similar analysis will show that the same results will be obtained when the two structures $B1$ and $B2$ are used for receiving.

It follows from the foregoing description of the apparatus of Fig. 1, that with the directional relay DR deenergized and its back contacts 19 and 23 closed, the inductors Ia and Ib are connected with the receiving apparatus to form a receiver immune to foreign space magnetic fields, and which provides a relatively high pick-up sensitivity. With the directional relay DR energized and its front contacts 30 and 35 closed, the transmitting apparatus is connected with the four inductors, Ia , Ib , Ic , and Id in series, to furnish a transmitter possessing relatively high mutual inductance with the traffic rails and a distribution of turns effective to transfer a high ratio of energy for a given power output of the transmitting apparatus.

The directional relay DR may be controlled by current supplied from any convenient source such as a battery (not shown), the circuit being governed by a manually operated controller or by a code device such as usually employed in systems of the type herein involved. As a matter of fact, the relay DR may be replaced by a manually operated controller should it seem desirable to do so.

The connection of the inductors and the coils thereof is here shown as series but it is not essential so long as the proper polarities are preserved.

It is possible to still further increase the power transfer by using more than two inductor structures, thus, to use four similar structures spaced apart on the vehicle along the trackway would substantially double the power transfer by the structure of Fig. 1, the resistance of the four structures being maintained equal to that of the two structures $B1$ and $B2$.

In Fig. 2, a modified arrangement of the inductors of Fig. 1 is provided, and in which the immune inductors Ia and Ib are used for receiving

the same as in Fig. 1, but for sending the inductors Ic and Id only are employed. In this instance, the horizontal coils 26 and 27 of inductor Ic and the coils 28 and 29 of inductor Id are serially connected with the transmitting apparatus over the front contacts 30 and 35 of the directional relay DR independent of the inductors Ia and Ib . It is clear that with the proper proportioning of the several coils of Fig. 2 this arrangement will produce results similar to that of the apparatus of Fig. 1.

In Fig. 3, another modified arrangement for the inductors mounted on the vehicle spaced apart along the trackway is provided. In this arrangement the coils that go to make up the inductors Ic and Id are located at the opposite corners of the vehicle. Four short bars $B3$, $B4$, $B5$, and $B6$ are mounted on the vehicle transverse to the traffic rails at the opposite ends of the vehicle, the bars $B3$ and $B4$ being over rail 1 and bars $B5$ and $B6$ over rail $1a$. These bars are similar to the bars $B1$ and $B2$ of Fig. 1, except for the fact that in this instance no vertical cores are constructed thereon. The coils 26 and 27 which make up inductor Ic are mounted on the bars $B4$ and $B6$, respectively, the arrangement being such that coil 26 is disposed above rail 1 and the coil 27 is disposed above rail $1a$. In like manner the coils 28 and 29 which make up the inductor Id are wound on the bars $B3$ and $B5$, respectively, the coil 28 being disposed above the rail 1 and the coil 29 being disposed above the rail $1a$. In other words, with the bars $B6$ and $B4$ mounted at the forward and rear ends of a vehicle the coil 27 is positioned above the rail $1a$ at the forward end of the vehicle and the coil 26 is positioned above the rail 1 at the rear end of the vehicle. In like manner, the coils 28 and 29 of the inductor Id are located above the rails 1 and $1a$ at the forward and rear end of the vehicle, respectively.

The inductors Ic and Id of Fig. 3 are connected in parallel with the input of the receiving apparatus RA over back contacts 36 and 37 of the relay DR as will be readily understood by an inspection of the drawing. With the relay DR energized and its front contacts 38 and 39 closed, the inductors are transferred to the transmitting apparatus TA. It is clear that the inductors Ic and Id of Fig. 3 when supplied with current will be effective to induce electromotive forces in the traffic rails that add their effects, and current flowing in the two rails in multiple will be effective to induce electromotive forces in the inductors that add their effect. I have found that the staggered arrangement of the inductor coils of Fig. 3 will not only give the increased transfer of power the same as the inductors of Fig. 1, but will also give a better balanced condition for the receiving and transmitting circuits.

Referring to Figs. 4 and 5, the reference characters 40 and 41 designate the two forward vehicles of a railway train, and the reference characters 42 and 43 designate the two rear vehicles of such train. For example, in Fig. 4, the vehicle 40 may be the locomotive, the vehicle 43, the caboose and the vehicles 41 and 42 cars of a freight train, the several vehicles being coupled together in the usual manner and the intervening cars being omitted from Fig. 4 for the sake of simplicity. In a train signaling system for telephoning between two spaced points on a train, for example, between the locomotive 40 and the caboose 43, apparatus embodying my invention will be mounted both on the caboose and on the locomotive, preferably on the tender of the locomotive.

comotive. As shown conventionally in Fig. 4, two structures B1 and B2 with their associated inductor coils are disposed at the opposite ends of the caboose 43 outside of the trucks. In like manner two bars and their associated inductor coils will be mounted at the opposite ends of the tender of the locomotive 40 as shown conventionally at B1 and B2 at the left-hand end of Fig. 4. It is clear that with the caboose 43 operated with either end first, one inductor bar will be ahead of the truck wheels and the other inductor bar will be behind the truck wheels.

Recalling that the communication current flows in the two traffic rails in multiple and returns through the ground path, it is clear that with the train of Fig. 4 moving to the left, and a pair of insulated rail joints 44 and 45, one in each rail comes between the rear truck wheels of the car 42 and the forward truck wheels of the caboose 43, the rail current, which ordinarily flows in the rails, will pass around the high resistance of the insulated rail joints 44 and 45 by flowing from the rails through the wheels and metal parts of the caboose, the coupler between the caboose 43 and car 42 and thence back into the rails through the metal parts and wheels of that car. To visualize this path for the current around the insulated rail joints 44 and 45, a dotted line is placed on Fig. 4 and an arrow is added to indicate the direction of the flow of current at a particular instance. Under such conditions the effectiveness of the inductor coils mounted on the bar B1 will be materially decreased. The inductive effectiveness of the coils mounted on the bar B2 at the rear of the caboose will, however, remain unchanged during this period that the insulated rail joints 44 and 45 pass between the car 42 and the forward truck wheels of the caboose and hence a momentary loss of control for the caboose apparatus will be avoided. In other words at locations where insulated rail joints are provided in connection with an automatic wayside signal system and which joints are staggered less than the distance between the rear wheels of the car 42 and the forward wheels of the caboose 43, the caboose inductor located at the rear end of the caboose will maintain the control of the equipment during the period these two insulated rail joints pass between the car 42 and the caboose 43. In the event a single inductor is mounted at one end of the caboose as heretofore proposed, a loss of control may occur as such insulated rail joints are passed, whereas by providing two inductors one at each end of the caboose, such loss of control will be avoided. In like manner the two inductors mounted on the opposite ends of the tender of locomotive 40 will function to prevent a loss of control for the locomotive equipment when a pair of insulated rail joints 46 and 47 (one in each rail) pass between the tender of the locomotive and the car 41.

In Fig. 5, the train of Fig. 4 is illustrated as having advanced to a position where the insulated rail joints 44 and 45 are under the bar B2 at the rear end of the caboose. Under this condition the rail current will tend to flow to ground by the distributed ground path in advance of the insulated rail joints as illustrated by the dotted lines of Fig. 5, and, consequently, will not flow under the inductor coils of B2. That portion of the current, however, that passes to ground between the location of the bar B1 at the forward end of the caboose and the insu-

lated rail joints will be effective to influence the inductor coils mounted on B1 and a momentary loss of control will be avoided. It will be apparent from an inspection of Fig. 3 that the staggered arrangement of the inductor coils will be effective for avoiding a momentary loss of control at insulated rail joint locations.

Although I have herein shown and described only certain forms of apparatus embodying my invention, it is understood that various changes and modifications may be made therein within the scope of the appended claims without departing from the spirit and scope of my invention.

Having thus described my invention, what I claim is:

1. An end to end railway train signaling system comprising a receiving apparatus and a transmitting apparatus on each of two vehicles of the train, a communication circuit between such vehicles including the traffic rails in multiple, and a circuit on each of said vehicles adapted to be connected to either the receiving or transmitting apparatus at that vehicle and including a plurality of windings, in inductive relation with each of the traffic rails to induce alternating current therein in multiple when the transmitting apparatus of that vehicle is connected with the circuit and to be responsive to current flowing through said rails when the receiving apparatus of that vehicle is connected with the circuit, and each of said circuits being characterized by having its windings distributed on the respective vehicle along the trackway for transfer of energy with the rails at the opposite ends of the vehicle whereby communication between the two vehicles is maintained while either of said vehicles passes over a pair of insulated rail joints one in each rail.

2. An end to end railway train signaling system comprising a receiving apparatus and a transmitting apparatus on each of two vehicles of the train, a communication circuit between such vehicles including the traffic rails in multiple, a first inductor on each vehicle mounted at one end of the vehicle and including two coils one disposed over each rail, a second inductor on each vehicle mounted at the other end of the vehicle and including two coils one disposed over each rail, a first circuit on each vehicle to connect the inductors of this vehicle with the transmitting apparatus to induce alternating current in the rails in multiple, a second circuit on each vehicle to connect the inductors of that vehicle with the receiving apparatus to inductively receive current in response to alternating current flowing in the rails in multiple, and a circuit controller on each vehicle effective to render either the first or the second circuit on the same vehicle active whereby two-way communication between the two vehicles is accomplished and maintained uninterrupted when either of said vehicles passes over a pair of insulated rail joints one in each rail.

3. In a railway train signaling system comprising a receiving apparatus and a transmitting apparatus on a vehicle of the train and a communication circuit including the traffic rails in multiple, in combination with the above instrumentalities a first and a second inductor on the vehicle each capable of inductively receiving electromotive forces due to a current flowing in the rails in multiple and of inducing electromotive forces in the rails when supplied with current and which forces cause current to flow in

the rails in multiple, circuit means for selectively connecting said inductors with either the receiving apparatus or with the transmitting apparatus, a first and a second coil for each inductor, said first coils being inductively coupled with one rail and said second coils being inductively coupled with the other rail, and said coils mounted on the vehicle for transfer of energy with the rails at the opposite ends of the vehicle where-
5 by the vehicle equipment remains effective to transfer energy with the rails as the vehicle passes over a pair of insulated rail joints one in each rail.

4. In a railway train signaling system comprising a receiving apparatus and a transmitting apparatus on a vehicle of a train and a communication circuit including the traffic rails in multiple, in combination with the above instrumentalities an inductor on the vehicle consisting
15 of two windings in series one winding inductively coupled to one rail and the other inductively coupled with the other rail with said one winding disposed over said one rail at the forward end of the vehicle and said other winding disposed
20 over said other rail at the rear end of the vehicle, and a circuit controller having different positions for selectively connecting said inductor to either the receiving or to the transmitting apparatus.

30 5. In a railway train signaling system comprising a receiving apparatus and a transmitting apparatus on a vehicle of the train and a communication circuit including the traffic rails in multiple, in combination with the above instrumentalities a first inductor on the vehicle consisting of two windings one inductively coupled to each rail with one winding disposed over one rail at the forward end of the vehicle and the other winding disposed over the other rail at
35 the rear end of the vehicle, a second inductor consisting of two windings one inductively coupled to each rail with one winding disposed over said one rail at the rear end of the vehicle and the other winding disposed over said other rail at the forward end of the vehicle, and a circuit controller having different positions for
40 selectively connecting said inductors in parallel to either the receiving apparatus or to the transmitting apparatus.

50 6. In a railway train signal system comprising a receiving apparatus and a transmitting apparatus on a vehicle of the train and a communication circuit including the traffic rails, in combination with the above instrumentalities two bars mounted on the vehicle transverse with the traffic rails and each provided with four vertical core members, a first winding for each bar including a portion wound on each core, a second winding for each bar including a portion wound on the bar substantially above each rail, a circuit controller having a first and a second position, a first circuit means effective in the first position of the controller to connect with the receiving apparatus the first windings of the two bars in series, said circuit means characterized by the fact that the portions of each winding are so connected together that electromotive forces induced therein due to current flowing in the rails in multiple are additive, and a second circuit means effective in the second position of the controller to connect with the transmitting apparatus the first and second windings of both bars in series, said second means characterized by
60 the fact that the electromotive forces induced in
65 the rails due to a current flowing in the several portions of said windings are additive.

7. In a railway train signal system comprising a receiving apparatus and a transmitting apparatus on a vehicle of the train and a communication circuit including the traffic rails, in combination with the above instrumentalities two inductors mounted on the vehicle in inductive relation with the traffic rails, a first winding for each inductor consisting of four vertical coils
10 two of which are on opposite sides of one rail and the other two of which are on opposite sides of the other rail, a second winding for each inductor consisting of a horizontal coil substantially above each rail, a circuit controller having
15 a first and a second position, a first circuit means effective in the first position of the controller to connect with the receiving apparatus the first winding of said inductors in series, and a second circuit means effective in the second position of the controller to connect with the transmitting apparatus the first and second windings of said inductors in series.

8. In a railway train signal system comprising a receiving apparatus and a transmitting apparatus on a vehicle of the train and a communication circuit including the traffic rails, in combination with the above instrumentalities two bars mounted on the vehicle each extending transversely across the rails and each having four
25 downwardly projecting legs, two of which are on opposite sides of one rail and the other two of which are on opposite sides of the other rail, a first winding for each bar made up of a coil on each leg, said coils being connected in series in
30 such manner that the electromotive forces induced therein by current flowing in the rails in multiple are additive, a second winding for each bar made up of a coil on the bar substantially above each rail, said coils being connected in
35 series in such manner that the electromotive forces induced in the rails by current flowing in the winding are additive, a circuit controller having different positions, a first circuit means effective to connect the first windings of the two bars
40 with the receiving apparatus and including one position of said controller, and a second circuit means effective to connect the second windings of the two bars with the transmitting apparatus
45 and including another position of said controller.

9. In a railway train signal system comprising a receiving apparatus and a transmitting apparatus on a vehicle of the train and a communication circuit including the traffic rails, in combination with the above instrumentalities, a first winding on the vehicle consisting of four vertical coils in series, two of which are on opposite sides of one rail and the other two of which are on opposite sides of the other rail, said winding being characterized by the fact that
50 the coils are so connected that electromotive forces induced therein by the magnetic field due to an alternating current flowing in the rails in multiple add their effects and electromotive forces induced therein by a space magnetic field
55 transverse to the rails cancel their effects, a second winding on the vehicle consisting of two horizontal coils in series one located substantially above each of the rails, said second winding characterized by the fact that the coils are so
60 proportioned that electromotive forces induced in the two rails are substantially equal and add their effects, a circuit controller having different positions, a first circuit means to connect said first winding with the receiving apparatus and in-
65

70 75

cluding one position of the controller, and a second circuit means to connect the second winding with the transmitting apparatus including another position of the controller.

5 10. In a railway train signaling system comprising a receiving apparatus and a transmitting apparatus on a vehicle of the train and a communication circuit including the traffic rails, in combination with the above instrumentalities 10 a first winding on the vehicle disposed in inductive relation with the traffic rails and consisting of a plurality of vertical coils in series, said winding being characterized by the fact that the coils are so proportioned and disposed with respect 15 to the rails as to be substantially immune to the effects of space magnetic fields transverse to the rails and electromotive forces induced therein due to current flowing in the rails in multiple are additive, a second winding on the vehicle 20 disposed in inductive relation with the traffic rails and consisting of a plurality of horizontal coils in series, said second winding characterized by the fact that the coils are so proportioned and disposed with respect to the rails that electromo- 25 tive forces induced in the rails due to a current flowing in said winding are additive, a circuit controller, a first circuit to connect the first winding with the receiving apparatus including one position of said controller, and a second circuit to 30 connect the second winding with the transmitting apparatus including another position of the controller.

11. Railway train signaling apparatus of the type comprising two magnetizable bars mounted on a vehicle transverse to the traffic rails and each provided with four downward depending magnetic cores two disposed on the opposite sides 5 of one rail and the other two disposed on the opposite sides of the other rail, a first winding for each bar including a portion wound on each of the cores of that bar and characterized by being serially connected that electromotive forces 10 induced therein due to current flowing in the rails in multiple are additive, and when supplied with current induce electromotive forces in the rails that add their effects, a second winding for each bar including a portion wound on the bar 15 substantially above each rail and characterized by being serially connected to induce in the rails electromotive forces which are additive when that winding is supplied with current, a circuit controller having a first and a second position, a 20 first circuit means including the first position of the controller effective to serially connect the first windings of said bars with a receiving apparatus for energizing a signaling device with current picked up from the rails, and a second 25 circuit means including the second position of the controller effective to serially connect both the first and second windings of said bars with a source of current for supplying current to the traffic rails.

PAUL N. BOSSART.
